TREATMENT OF HYDROCARBON OIL

Roland B. Day, Chicago, Ill., assignor to Universal Oil Products Company, Chicago, Ill., a corporation of South Dakota

Application February 11, 1932. Serial No. 592,210

6 Claims. (Cl. 196—36)

This invention refers more particularly to the treatment of cracked hydrocarbon distillates of approximate motor fuel boiling range though straight run distillates of similar character and 5 of higher boiling range than gasoline may also be treated.

Cracked distillates sometime contain large amounts of gum-forming constituents such as the di and tri olefins and sulfur compounds which 10 include representatives of various groups such as mercaptans, thioethers, thiophenes, etcetera, along with considerable percentages of hydrogen sulfide.

In a more specific sense the invention has reference to a process for the treatment of hydrocarbon oil vapors whereby the distillates produced by their subsequent fractionation may be so refined and stabilized that further chemical treatment may not be necessary to fit them for consumption, and if any further treatment is necessary, it is only of a minor character.

The present invention is directed to the treatment of cracked hydrocarbon oil vapors for the removal of the gum-forming and sulfur compounds mentioned and possesses the advantages of ready applicability, ease of operation and low cost.

In one specific embodiment the invention comprises treating hydrocarbon oils, particularly 30 cracked hydrocarbon oil distillates, while in heated vaporous condition with hydrochloric acid and/or other halogen acids while in contact with metallic catalysts, the catalysts having been previously activated or preconditioned before use in 35 the process by treatment with hydrochloric acid.

The exact nature and features of the process may be conveniently described with reference to a characteristic operation, and this description will be given in connection with the attached 40 drawing which shows diagrammatically in side elevation a plant layout in which the operations may be conducted though the particular apparatus shown is only illustrative of many others from which it differs only in minor details.

Referring to the drawing, the apparatus will be seen to consist of a treater 7 in which the solid contact materials may be disposed in the best manner for affording intimate contact of the mixture of halogen acid and oil vapors therewith, a 45 fractionator 27 for final rectification of the treated vapors and the usual condensing and collecting equipment.

Oil vapors to be treated may be admitted to the system through a line 1, containing a control 55 valve 2, valve 2 permitting reduction or release

of pressure if it be found advantageous to employ lower pressures than those under which the vapors have been generated. Since either upward or downward flow of the vapors and acid over the solid contact materials may be employed, treater 60

7 is shown provided with the necessary lines for permitting either type of flow. When downflow treatments are to be conducted, the entering vapors may be passed through a line 3 containing a control valve 4 to upper vapor space 9 above 65 the bed of contact material 8, and when upflow treatments are more suitable for any reason, the vapors may be diverted through line 5, containing control valve 6, and enter lower vapor space 10 below the perforated support 8'. The halogen acid employed may also be admitted to either the upper or lower vapor spaces of the treater, and since this acid will be hydrochloric in the majority of cases unless minor amounts of the other halogen acids are considered, the description will 70 be confined to the use of this acid. To provide for its admission to the system, a line 13, containing a control valve 14, is shown, this line branching into line 15, containing control valve 16 and terminating in distributing means 16' and 75 line 17, containing control valve 18, and terminating in distributing means 18'. The acid may be introduced as the anhydrous gas or as a solution of varying concentration, though in upflow treatments it may at times be preferable to utilize 80 the gas instead of the solution for reasons of distribution. In either event the mixture of hydrocarbon oil vapors and hydrochloric acid in proper amount is introduced to the treater and caused to flow upwardly or downwardly over the contact 85 materials.

The pre-conditioning of the contact material in the treater may be effected in several ways. For example, the mass may be treated by allowing concentrated hydrochloric acid to percolate 90 through it until the desired degree of chloride formation is accomplished or the metals may be chlorinated by contact with hydrochloric acid vapor generated conveniently by heating concentrated hydrochloric acid in the bottom of the tower. Also, the necessary amount of acid may be introduced as a substantially anhydrous gas or mixed with a certain amount of water vapor, the gas or vapor mixture having been generated in a small still of some sort, exterior to the treating plant shown in the drawing.

In addition to the use of hydrochloric acid for preconditioning contact masses, it may also be employed to regenerate their activity at a time when their catalytic effect has reached a low 100

value on account of gradual contamination by carbonaceous depositions, the formation of sulfur compounds and the disintegration of composite masses. The general effect of the hydrochloric acid used in such cases will be equivalent to a washing to remove the contaminating substances and expose fresh metallic and chloride surfaces, the limits of such a treatment being fixed only by the fact that the more soluble metallic chlorides in the mixture will be gradually removed until the mass no longer contains metals in the desired proportions.

The contact materials may be employed in space 8 of treater 7 as a substantially uniform mass of proper sized particles to afford contact without unnecessary resistance to flow or they may be employed in layers of alternating or progressively varying composition or supported upon regularly spaced trays. When downflow treatments are conducted a certain amount of condensation may occur, although this may be prevented if found desirable by preliminary superheating of the vapors or by heating the treater to prevent drop in temperature. When upflow treatments are conducted, a certain amount of fractionation may occur if no special precautions are taken to prevent condensation. In any event the conditions of operation in the treater will be regulated to produce the desired results. The treater is shown provided with manheads 11 and 12 for admission of contact materials and for their rejection when spent.

Vapors resulting from upflow treatments may be passed from the treater through line 19, containing control valve 20, and either passed directly, if sufficiently fractionated, to a condenser through line 23, containing control valve 24, and line 30, containing control valve 31, or if further fractionation appears advantageous or desirable they may be diverted through line 25, containing control valve 26, and enter the fractionator through line 21, containing control valve 22.

Vapors from downflow treatments may undergo a rough preliminary separation into vapors and non-vaporized liquids consisting of hydrocarbon oil polymers and derivatives and other reaction products, the vapors being passed to the fractionator through line 19', containing control valve 20', and the oils and other liquids being conducted from the bottom of the vapor chamber through line 45, containing control valve 46, to accumulator 47. This accumulator may have a line 48 connecting it with the vapor space of the treater to prevent gas lock. The liquid accumulations comprising those already described and the refluxes from fractionator 27 entering the accumulator from line 49, containing control valve 50, may be withdrawn therefrom through a line 51, containing control valve 52, and pumped by a pump 53 through a line 54, containing control valve 55, to any suitable point of disposal.

Vapors from fractionator 27 may pass through line 28, containing control valve 29, and thus by way of line 30, containing control valve 31, to condenser 32 which serves the purpose of liquefying gasoline fractions and cooling fixed gases, the mixture passing through line 33, containing control valve 34, to receiver 35. From this point the fixed gases may be withdrawn through line 36, containing control valve 37, at a rate consistent with the maintenance of suitable back pressure upon preceding portions of the equipment and the treated gasoline constituting the end product of the process may be withdrawn to

storage or other mild final treatment through line 38, containing control valve 39. To assist in controlling the boiling point range of the vapors from the fractionator, a suitable portion of the end product liquids may be returned to the top of the fractionator, these portions being led to recirculating pump 42 through line 40, containing control valve 41, and discharged therefrom through line 43, containing control valve 44.

I have found that the use of contact materials as described produces improved results in the treatment of hydrocarbon vapors to reduce gum-forming constituents and sulfur compounds. It will be evident that owing to the wide range in composition of the contact mass that it may be proportioned to give treatments of a more distinctly polymerizing character or of a more pronounced desulfurizing action. Thus, in general when polymerization is the main object as may occur when treating cracked vapors produced from paraffinic charging stocks of low sulfur content, the masses may contain relatively larger proportions of electro-positive metals, such as zinc and tin, whose chlorides have known polymerizing value. When a desulfurizing treatment is necessary, the proportion of electro-negative metal such as copper, silver, etcetera, may be somewhat increased. To account for the desulfurizing tendency of the contact masses thus employed in the presence of hydrochloric acid, it may be presumed that while the sulfur in organic combination has greater affinity for the electro-negative metal and that corresponding sulfides are formed as intermediate products, these are decomposed due to the joint action of hydrochloric acid and the chloride of the electro-positive metal, to liberate hydrogen sulfide. While this theory may not be entirely adequate to explain the complex reactions that are probably involved, the observations are definite to the effect that greater desulfurization is accomplished when using contact masses of the character described than when using compounds of electro-positive or electro-negative metals alone.

In regard to the polymerizing effects observed, these may be accounted for either on the basis of the presence of chlorides of electro-positive metals such as zinc, tin, iron, etcetera, these chlorides having known polymerizing value, or upon the action of hydrochloric acid per se in contact with electro-negative metals such as copper or silver, the latter functioning more in a catalytic sense.

As an example of the value of the preconditioning of the contact masses which constitutes the chief feature of the present invention a case involving the use of brass turnings in a copper lined treating tower may be considered. When such a contact mass is used without preliminary treatment of hydrochloric acid it may be necessary to pass the hydrocarbon vapors mixed with hydrochloric acid over the mass for several hours before the maximum treating effect is observed, indicated by improvement in color and reduction in gum and sulfur content. By preliminarily treating the brass turnings by percolating warm concentrated hydrochloric acid through them, the effect of the contact mass when the mixture of hydrocarbon vapors and hydrochloric acid is passed over them is immediately evident, the treating effect attaining its maximum possible under the conditions of treatment in a very short time. Thus, it is shown that the preliminary treatment increases the overall efficiency of the

process by increasing the time during which the mass is available for treatment.

The preceding specification and data upon the results obtainable by the use of the improved 5 treating process which it covers are sufficient to enable one skilled in the art to appreciate its value, but both specification and the example are given for illustrative purposes only and are not to be considered in the light of imposing undue limitations upon the scope of the invention.

10 I claim as my invention:

1. In processes of the character wherein hydrocarbon oil is refined to remove color, gum-forming and sulphur-containing components by 15 subjecting the same while in heated condition to the action of hydrochloric acid while in contact with a metallic catalyst, the improvement which comprises preconditioning and activating said metallic catalyst by subjecting the same to the 20 action of hydrochloric acid prior to contact with the hydrocarbon oil.

2. In processes of the character wherein hydrocarbon oil is refined to remove color, gum-forming and sulphur-containing components by 25 subjecting the same while in heated condition to the action of hydrochloric acid while in contact with a metallic catalyst comprising zinc, the improvement which comprises, preconditioning and activating said metallic catalyst by subjecting the same to the 30 action of hydrochloric acid prior to contact with the hydrocarbon oil.

3. In processes of the character wherein hydrocarbon oil is refined to remove color, gum-forming and sulphur-containing components by 35 subjecting the same while in heated condition to the action of hydrochloric acid while in contact with a metallic catalyst comprising copper, the improvement which comprises precondition-

ing and activating said metallic catalyst by subjecting the same to the action of hydrochloric acid prior to contact with the hydrocarbon oil.

4. In processes of the character wherein hydrocarbon oil is refined to remove color, gum-forming and sulphur-containing components by 80 subjecting the same while in heated condition to the action of hydrochloric acid while in contact with a metallic catalyst comprising a mixture of zinc and copper, the improvement which comprises preconditioning and activating the said metallic catalyst by subjecting the same to the action of hydrochloric acid prior to the introduction of the hydrocarbon oil.

5. In processes of the character wherein hydrocarbon oil is refined to remove color, gum-forming and sulphur-containing components by 85 subjecting the same while in heated vaporous condition to the action of the hydrochloric acid while in contact with a metallic catalyst comprising an alloy of zinc and copper, the improvement which comprises preconditioning and activating the said metallic catalyst by subjecting the same to the action of hydrochloric acid prior to the introduction of the hydrocarbon 90 vapors.

6. In processes of the character wherein hydrocarbon oil is refined to remove color, gum-forming and sulphur-containing components by 95 subjecting the same while in heated vaporous condition to the action of hydrochloric acid while in contact with a metallic catalyst comprising brass, the improvement which comprises preconditioning and activating the said metallic catalyst by subjecting the same to the action of hydrochloric acid prior to the introduction of the 100 hydrocarbon vapors.
